IN-LINE CLASP CONNECTOR

Irving Frederick Matthyse, New York, N. Y., assignor to Burndy Engineering Company, Inc., a corporation of New York

Application August 21, 1951, Serial No. 242,872

5 Claims. (Cl. 339—47)

My invention relates to connectors and more particularly to clasp connectors which can be longitudinally and positively locked and unlocked.

In my prior application 528,991, filed March 31, 1944, of which this present invention is an improvement, I disclose a clasp type connector having identical halves each composed of a ferrule and an integrally extending flat blade having a transversely bent over clip. The connection is made by placing one blade on the other in a criss-cross position, substantially at right angles, pivoting the halves until they are aligned, and thereafter pulling the halves until the clips abut each other to prevent further longitudinal separation.

While this connector functions satisfactorily in many respects and is presently used in large quantities, it requires considerable slack in the connecting wires to permit the jack-knifing action. In addition, this type of connector requires adequate lateral space to permit crossing one half over the other.

Accordingly, a principal object of my invention is to provide a connector in which the counterpart halves can be connected and disconnected substantially along the longitudinal axis thereby eliminating the need for considerable slack in the wires and lateral clearance for movement of the parts.

In the prior jack-knife connectors, the counterpart halves could not be completely insulated prior to making the connection as the connecting halves had to be free of insulation in order to permit the necessary lateral movement. The insulation for the connection was usually in the form of a loose elastic sleeve pushed back over one of the conductors until the counterpart halves were connected and then pulled over the completed connection to provide the necessary insulation.

Therefore another important object of my invention is to provide a connector in which the counterpart halves may be insulated prior to making the connection, and which insulation may be grasped during disconnection. The insulation may additionally serve as a means to guide the blades into engagement.

Further objects of my invention are to provide a connector having counterpart halves that are longitudinally self-aligned into locking position when the halves are pushed together; to provide a connector wherein the connector halves are positively locked against longitudinal separation or vibration; to provide a supplemental locking means to prevent accidental separation; and to provide a connector which has a minimum of parts, free of springs or the like, and which can be easily and economically fabricated of sheet material.

I accomplish these and other objects and obtain my new results as will be apparent from the device described in the following specification, particularly pointed out in the claims, and illustrated in the accompanying drawing, in which—

Fig. 1 is a plan view of a connector half;

Fig. 2 is a side elevation thereof;

Fig. 3 is a plan view of the counterpart halves, partially

2

in section, attached to their respective conductors, each connector half inserted in the other with the edges of the clip portions engaging to start the self-aligning action;

Fig. 4 is a similar view with the connector halves completely inserted in one another and aligned along their longitudinal center line;

Fig. 5 is a similar view of the connector halves locked together after being pulled longitudinally;

Fig. 6 is a bottom plan view of the connection in Fig. 5, 10 the connector halves being provided with insulation jackets abutting to form a sealed connection; the insulation shown in section;

Fig. 7 is a transverse sectional view of the connection in Fig. 5 taken along line 7—7; and

Fig. 8 is a modified connector half where its insulation jacket forms a guide means when the connector halves are being assembled.

In the drawings, reference numeral 10 designates a connector half made of the conventional conductive material, 20 such as copper, having a ferrule portion 12 which may be indented to the bared end 14 of an insulated conductor 16. A shroud portion 18 is provided to accommodate the insulation of the conductor.

From the ferrule a flat tongue or blade 22 extends, 25 having a transversely bent over clip 24 forming an up-raised portion. The blade terminates in a rounded free end 25 formed into a flat engaging means or hook 26. The clip is preferably spaced apart from the blade a distance slightly less than the thickness of a counterpart 30 blade, and may be integrally attached to the blade along an oblique line forming a clip base 28 slanting outwardly toward the free end of the blade. The slanted clip base 28 acts to guide the free end of the counterpart blade longitudinally when the parts are pushed together. The 35 hook 26 is formed by a recessed portion or slot 30 having oblique sides that conform substantially to the base 28 of a counterpart clip which it engages. A hump 32 is upset on the clip side of the blade between the clip and the ferrule, and engages the rounded end of the counterpart blade forming a supplemental locking means when the parts are interengaged, as is shown in Fig. 5.

A cam face 34 integrally formed along the blade 22 on the side opposite the clip portion 24 projects sufficiently above the blade surface to guide the rounded end 45 of the counterpart blade in longitudinal alignment when inserted. The cam face also functions as a stop and prevents separation of the blades if they are accidentally disengaged. The leading edges of the clips 24 and the rounded free ends of the blades may be beveled to facilitate entry of the parts and the camming action.

Figures 3—6 inclusive illustrate the identical connector halves 10 and 10a respectively, the corresponding parts of the connector half 10a being similarly identified, in various stages of engagement.

Each connector half 10 and 10a are longitudinally brought together with the free ends 25 and 25a of the respective blades inserted under the corresponding clips 24a and 24. This movement causes a wiping action between the flat or plane surfaces of the blades and the clips and insures a good electrical contact. As the blades are forced together, their free ends may engage the inner surfaces of the bases 28 and 28a respectively, on the clips which guide the blades slightly off the longitudinal center-line of the connector to their interlocking position. The 55 cams 34 and 34a guide the blade when it is too far out of alignment on the other side of the connector halves and cam it into locking position upon continued insertion. As will be noted in Fig. 8, an insulation jacket aids in maintaining this alignment.

When the forward edges of the bases 28 and 28a of the clips first engage, as seen in Fig. 3, the connector halves are fully inserted, and upon further longitudinal

pressure the connector halves move upon one another in a self-aligning action. The free ends of the blades are moved until the hooks 26 and 26a are aligned with their respective bases 28 and 28a on the clips. In this position the free ends of the blades have slid over the humps 32 and 32a, which additionally insure a wiping action between blades and clips by springing the blade ends slightly away from each other.

The connection is completed by a longitudinal pull on the connector halves causing the hooks to slide longitudinally and acting as a catch, engage the bases of the clips, as illustrated in Fig. 5. As shown in Figs. 5 and 6 the attached connector halves are in complete longitudinal alignment. The oblique sides of the slots 30 and 30a snugly engage the correspondingly shaped bases of the clips. In this position the humps are adjacent the blades and bear against the edges thereof to prevent accidental separation. If the hook 26 and 26a are loosened from their respective clips for any reason, the cam faces 34 and 34a will prevent release of the parts until the connector halves are manually adjusted to permit separation.

Unless this manual adjustment occurs, a longitudinal pull on the connector halves will cause the hooks to re-engage with their respective bases. Therefore, in order to disconnect the connector halves they must be pushed together to unlatch the hooks, against the resistance offered by the humps and then slightly adjusted laterally to enable the hooks to clear the base portions of the clips.

In Fig. 6 the connector parts are provided with insulation jackets 36 and 36a which may be mounted over insulation sleeves 38 and 38a, made of nylon or the like, through which the ferrule portions 12 and 12a may be indented to the bared end of the conductor, as is for example shown and described in Patent No. 2,429,585 issued to J. Rogoff. In the present construction, each insulation jacket may be pre-assembled on each connector half allowing sufficient space on the sleeve for indenting the ferrule to the conductor through the sleeve. If the insulation jackets are made of suitable indentable material, the insulation sleeve may be omitted, and the jacket made to extend over the ferrule portion of the connector half for identification thereto.

Each insulation jacket extends toward the free end of the blade sufficiently to cover the clip portion allowing the remaining portion of the blade to be bare for insertion into the counterpart connector half. If the insulation is made of resilient material the ends of the jackets may be shaped in the form of lips 39 and 39a which resiliently abut one another and provide a sealed connection. If the insulation jackets are of a rigid material the ends of the jackets may be lapped.

When resilient insulation jackets 40 are utilized as shown in Fig. 8, the cam faces 34 and 34a may be omitted, for the insulation jacket will press the blades of the connector halves into proper alignment. The reversed action will be required for separation. The blade 42 in this modification is shown with a shoulder 44 formed normal to the longitudinal axis which abuts the counterpart of clip 46. The insulation jacket 40 may extend around the outer end of the clip 46 to be anchored thereto as at 48.

In providing a hook at the end of each blade member of a clasp type of connector, I can lock the connector halves together by a push-pull movement without a knifing or wristlock movement. The locking means of the counterpart connector halves are self aligning when the connector halves are longitudinally pushed together, so that a subsequent pull will lock the parts. As little side motion is required, I can insulate each connector half prior to making the connection with an insulation jacket that will not interfere with the making or breaking of the connection. Each connector half

will be locked securely in position and cannot be separated by application of a longitudinal force in either direction or by severe vibration. I can utilize the bent-over clips to insure a firm electrical engagement between the blades of the connector halves, and form an anchorage for the hook portions of the blades. The connector halves may be identically fabricated of sheet metal or tubular stock which feature facilitates production and minimizes storage of different parts.

I have thus described my invention, but I desire it understood that it is not confined to the particular forms or uses shown and described, the same being merely illustrative, and that the invention may be carried out in other ways without departing from the spirit of my invention, and, therefore, I claim broadly the right to employ all equivalent instrumentalities coming within the scope of the appended claims, and by means of which, objects of my invention are attained and new results accomplished, as it is obvious that the particular embodiments herein shown and described are only some of the many that can be employed to attain these objects and accomplish these results.

I claim:

1. A separable connector which comprises a blade portion and a ferrule portion adapted to be secured to a wire, said blade having a plane surface portion adapted to lie in face-to-face contact with the corresponding portion of a counterpart connector when interengaged, an upraised portion adjacent an edge of the blade, and means extending from an edge of the blade portion and adapted to press the plane surface portion of the counterpart blade into contact therewith as the counterpart blade is longitudinally inserted therebetween, flat engaging means in the blade and formed in the shape of a hook and lying in the plane surface portion of the blade at the end of the blade to engage an upraised portion of the counterpart connector positioned adjacent the edge thereof to lock the connectors against separation.

2. A separable connector which comprises a blade portion and a ferrule portion adapted to be secured to a wire, said blade having a plane surface portion adapted to be in face-to-face contact with the corresponding portion of a counterpart connector when interengaged, an upraised portion adjacent an edge of the blade, and means extending from an edge of the blade portion and adapted to press the plane surface portion of the counterpart blade into contact therewith as the counterpart blade is inserted therebetween, said blade having a transverse recessed portion formed in and lying in the plane of the blade and adapted to engage an upraised portion of the counterpart connector to lock the connectors positioned adjacent the edge thereof against separation.

3. A separable connector which comprises a blade portion and a ferrule portion adapted to be secured to a wire, said blade having a plane surface portion adapted to lie in face-to-face contact with the corresponding portion of a counterpart connector when interengaged, a clip extending from an edge of the blade portion and adapted to press the plane surface portion of the counterpart blade into contact as the counterpart blade is longitudinally inserted therebetween, said blade having a recessed portion lying in the plane surface of the blade from the same edge as the clip, and adapted to engage the clip of the counterpart blade to lock the connectors against separation, and a cam portion projecting from the opposite edge of the blade as is positioned the clip, for directing the blade portion of the counterpart blade into contact with said clip.

4. A separable connector which comprises a blade portion and a ferrule portion adapted to be secured to a wire, said blade having a plane surface portion adapted to lie in face-to-face contact with the corresponding portion of a counterpart connector when interengaged, a clip extending from an edge of the blade portion and adapted

to press the plane surface portion of the counterpart blade into contact therewith as the counterpart blade is longitudinally inserted therebetween, said clip connected to its blade along a line oblique to the longitudinal centerline of the connector and directed laterally outwardly toward the end of the blade to guide the counterpart blade into engagement therewith, hook-like means lying in the plane surface portion and at the end of the counterpart blade to engage said clip.

5. A separable connector which comprises a blade portion and a ferrule portion adapted to be secured to a wire, said blade having a plane surface portion adapted to lie in face-to-face contact with a counterpart connector when interengaged, a clip extending from an edge of the blade portion and adapted to press the plane surface 15 portion of the counterpart blade into contact therewith as the counterpart blade is inserted therebetween, catch means in the form of a hook at the end of the blade and lying in and movable on the plane surface to engage the clip of the counterpart connector and lock the connectors 20

against separation, and a flexible insulation jacket mounted on the ferrule and extending over the blade to cover the clip, and adapted to non-rotatably engage the insulation jacket of the counterpart connector, whereby a counterpart connector and insulating jacket may be locked thereto by a movement only in the plane surface of the blade portion.
